DESIGN FOR A TRUCK BODY

Clement H. Tuke, Austin, Tex., assignor to Tips
Engine Works, Austin, Tex.

Application August 14, 1940, Serial No. 94,422

Term of patent 14 years

To all whom it may concern:

Be it known that I, Clement H. Tuke, a citizen of the United States, residing at Austin, in the county of Travis and State of Texas, have invented a new, original, and ornamental Design for a Truck Body, of which the following is a specification, reference being had to the accompanying drawing, forming part thereof.

I claim:

The ornamental design for a truck body, as shown.

CLEMENT H. TUKE.
